(57) **CLAIM**

The ornamental design for a display screen portion with animated graphical user interface as shown and described.

DESCRIPTION

FIG. 1 is a front view of a first image of a display screen portion with animated graphical user interface, showing my new design; and,

FIG. 2 is a front view of a second image thereof.

The outermost broken lines in FIGS. 1 through 2 illustrate a portion of a display screen and form no part of the claimed design. The other broken lines showing of text in FIG. 2 represents environmental subject matter and forms no part of the claimed design.

The appearance of the animated image sequentially transitions between the images shown in FIGS. 1-2.

The process or period in which one image transitions to another forms no part of the claimed design.

1 Claim, 2 Drawing Sheets
